UNITED STATES PATENT OFFICE.

SAMUEL FORTER, OF NEW CASTLE, PENNSYLVANIA.

REVERSE-VALVE.

SPECIFICATION forming part of Letters Patent No. 603,103, dated April 26, 1898.

Application filed October 8, 1897. Serial No. 654,575. (No model.)

To all whom it may concern:

Be it known that I, SAMUEL FORTER, a citizen of the United States, residing at New Castle, in the county of Lawrence and State of Pennsylvania, have invented or discovered new and useful Improvements in Reverse-Valves, of which the following is a specification.

In the accompanying drawings, which make part of this specification, Figure 1 is a vertical section of my invention along the line 11 in Fig. 4. Fig. 2 is a plan view of my improved bed-plate. Fig. 3 is a side elevation of my invention complete. Fig. 4 is an end elevation of the same. Fig. 5 is a sectional view along the line 55 in Fig. 1; and Fig. 6 is a like section of the bed-plate, shown with the superstructure removed.

My invention, generally speaking, consists of certain improvements more especially on that class of reverse-valves covered by Letters Patent to myself, No. 577,019.

More particularly these improvements consist in an oscillating water-seal reverse-valve so constructed that the deposit of tar, &c., in the bed-plate will not interfere with the successful operation of the valve, and that such deposit may be conveniently removed while the valve is in operation, and that all operative parts—such as links 11, shafts 7 and 8, and valve-shell 6—can be removed from their positions without disturbing the outside casing.

In the several views which constitute part of this specification, 1 is a bed-plate fitted with flanged gas-apertures 1^a, 1^b, and 1^c and surrounded by flanged edge 2. Extending laterally on bed-plate 1 from the flanged apertures 1^a and 1^c are ribs 3 3, said ribs being of less height than said flanged edges, which are in turn of equal height with the flange 2, surrounding the bed-plate 1. Extending longitudinally on bed-plate 1 from apertures 1^a and 1^c are ribs 3^a 3^a of like height with ribs 3 3. When bed-plate 1 is filled with water, said ribs are all submerged. Upon ribs 3 3 is supported casing 4, provided with cleaning-doors 4^a 4^a and gas or air connection 4^b. The bottom of casing 4 is of less size than the bed-plate 1, thus leaving an open space between casing 4 and the flange 2, through

which hooks may be inserted to clean bed-plate 1 of deposited tar.

5 5 are Z-irons placed laterally along the edges of casing 4, serving to strengthen the 55 same and also acting as a support for a brick lining for said casing.

6 is the valve-shell, provided with hooks 6^a 6^a to assist in its removal.

7 and 8 are shafts oscillating in raised open 60 bearings 7^a 7^a and 8^a 8^a on bed-plate 1, said bearings being of less height than flange 2, so that when said bed-plate is filled with water said bearings and said shafts are submerged. 65

10 10 are integral pins on valve-shell 6.

11 11 are links forged at their lower extremities to shafts 7 and 8 and slotted at their upper extremities to receive pins 10 10 on valve-shell 6. 70

12 is the operating-lever bolted to one of the links 11 and provided at its upper end with weight 13, to which it is attached by chain 14, running between guide-pulleys 15 15. Weight 13 is cut away, as at 13^a, to avoid 75 the base of lever 12 when said weight descends.

16 16 are the water connections of bed-plate 1.

The operation of my device is as follows: 80 Suppose the valve-shell to be in the position shown in Fig. 1, connecting apertures 1^b 1^c. The bed-plate, being filled with water, forms a perfect water-seal for the valve. To reverse the valve, the operating-lever 12 is thrown 85 over, assisted in its movement by weight 13. The reversal of operating-lever 12 will cause the shaft 7 to turn, and with it links 11 11, keyed thereto. This motion would cause the valve-shell 6 to move on links 11 11, forged 90 to shafts 7 and 8, and be carried through an arc until it rested in the position shown by the dotted lines in Fig. 1, thus connecting apertures 1^a and 1^b.

The following are some of the beneficial 95 features of my improved valve: The tendency in water-seal reverse-valves is for tar to collect in the bottom thereof, destroying the integrity of the water seal and clogging the operation of the reversing mechanism. It 100 has also been impossible heretofore to clean out such deposit while the valve is in use.

In my improved reverse-valve I elevate both the casing and the valve-shell on submerged ribs rising from the bottom of the bed-plate, leaving beneath a clean space for the deposit of tar, &c., on the bottom of the bed-plate, so rendering it impossible for such deposit to reach and interfere with the operation of the reversing mechanism.

The open space surrounding the base of casing 4 within flange 2 enables a hook to be inserted and the tar removed from every portion of the bed-plate.

The valve-shell, links, and shafts may be readily removed through doors 4^a 4^b without disturbing casing 4 by disconnecting lever 12 from the link 11, to which it is bolted.

Having described my invention, what I wish to claim is—

1. In reverse-valves, the combination of a bed-plate; means for adapting said bed-plate to act as a water seal; ports in said bed-plate; projections on said bed-plate of less height than the walls of the water seal; a valve-shell resting on said projections; means for oscillating said valve-shell, and a casing resting on said projections.

2. In reverse-valves, the combination of a bed-plate; means for adapting said bed-plate to act as a water seal; ports in said bed-plate; projections on said bed-plate of less height than the walls of the water seal; a valve-shell resting on said projections; means for oscillating said valve-shell, and a casing resting on said projections.

lating said valve-shell, and a casing resting on said projections, at an interval within the walls of said water seal.

3. In reverse-valves the combination of a bed-plate, means for adapting said bed-plate to act as a water seal; ports in said bed-plate; bearings erected on said bed-plate and of less height than the walls of the water seal; oscillating shafts resting on said bearings; ribs on said bed-plate of less height than the walls of said water seal; a valve-shell resting on said ribs; links operatively connecting said shell and said shafts; a reversing-lever connected to one of said links, and a casing resting on said ribs at an interval within the walls of the water seal.

4. In reverse-valves the combination of a bed-plate; means for adapting said bed-plate to act as a water seal; projections on said bed-plate of less height than the walls of the water seal; a valve-shell resting on said projections; means for causing said valve-shell to oscillate and a casing resting on said projections; said operating parts being removable through an aperture in said casing without disturbing the same.

In testimony whereof I have hereunto set my hand this 6th day of October, A. D. 1897.

SAMUEL FORTER.
